United States Patent Office

Des. 198,594
Patented July 7, 1964

198,594

TOTE BOX

Carmin A. Castellano, Dalton, Pa., assignor to Consolidated Molded Products Corporation, Scranton, Pa., a corporation of Delaware

Filed Jan. 20, 1964, Ser. No. 78,326

Term of patent 14 years

(Cl. D58—12.6)

I claim:

The ornamental design for a tote box, as shown.
